UNITED STATES PATENT OFFICE.

BENEDICT J. GRASBERGER, OF BUMPASS, VIRGINIA.

DESIGN FOR A WOODEN SPOON.

52,878.

Specification for Design.

Patented Jan. 14, 1919.

Application filed April 9, 1918. Serial No. 227,574. Term of patent 14 years.

To all whom it may concern:

Be it known that I, BENEDICT J. GRASBERGER, a citizen of the United States of America, residing at Bumpass, in the county of Louisa and State of Virginia, have invented a new, original, and ornamental Design for a Wooden Spoon, of which the following is a specification, reference being had to the accompanying drawing, forming part thereof.

In the drawings,
Figure 1 is a plan view of a spoon, showing my new design,

Fig. 2 is an edge view of the same,
Fig. 3 is a bottom plan view.

I claim

The ornamental design for a wooden spoon as shown.

BENEDICT J. GRASBERGER. [L. S.]
